UNITED STATES PATENT OFFICE.

LORIN W. YOUNG, OF NEW YORK, N. Y.

PORABLE LAMP.

1,352,862.

Specification of Letters Patent. Patented Sept. 14, 1920.

Application filed May 3, 1918. Serial No. 232,195.

To all whom it may concern:

Be it known that I, LORIN W. YOUNG, a citizen of the United States, residing at 43 W. 9th street, New York, in the county 5 of New York and State of New York, have invented certain new and useful Improvements in Portable Lamps, of which the following is a full, clear, and exact description, such as will enable others skilled in the art 10 to which it appertains to make and use the same.

This invention relates to illuminating devices and is directed, in its more specific features, to improvements in portable fixtures, such as floor and table lamps.

One of the objects of the invention is to provide an improved ornamental lighting fixture which controls and modifies the rays from the illuminant to produce an especially 20 uniform and agreeable light distribution.

A further object is to provide an improved portable electric lamp, of the more expensive type, in which all the light rays are well diffused to insure complete absence of glare 25 or shadow and by which a soft and decorative lighting effect is obtained with a minimum current cost.

Other objects and advantages of the invention will be in part noted hereinafter in connection with the following description of 30 the accompanying drawing which illustrates a typical embodiment of the invention and in which—

Figure 1 is a side view, half in elevation 35 and half in section, of a table lamp; and

Fig. 2 is a plan view of the diffusing reflector and supporting frame or bracket shown in Fig. 1.

The lamp illustrated comprises, in general, a vase standard 1 with a concealed incandescent element 2 and a reflector 3 arranged to direct the light rays upwardly against a diffusing reflector 4 supported by a frame 5. An ornamental translucent shade 45 fits about the reflector 4 and spreads downwardly to substantially the upper horizontal plane of the vase 1 in such a relation that all of the rays emerge from the lamp after having been filtered through the shade or diffused from the inner surface of the latter and from reflector 4.

Referring more specifically to the drawing, the standard 1, preferably in the form of a vase as shown, constitutes a support for 50 the light socket 7 and also the cupped reflector 3. The latter for this purpose may

have its flaring open end provided with a flange 8 which seats on the upper edge of the vase and therefore centers the reflector, as well as closes the vase body against the entry of foreign matter. A suitable switch 9 to control the light may be mounted where desired, for example, at the bottom of the standard. The reflector 3 is opaque and provided with a reflecting or diffusing surface. Its shape may vary in detail, but it is curved to direct upwardly the light rays against the diffusing surface of the inverted conical reflector 4 which is positioned thereabove with its apex in substantial alinement with the center of the illuminating element 2. The reflector 4, moreover, preferably has its surface of a dull or mat white to insure thorough diffusion of the rays which impinge thereon and to modify or soften the lighting effect.

The frame or bracket 5 includes a lower ring 10 which snugly fits the upper end of the vase and rests upon the annular flange 8 of the reflector 3. Fixed at equi-distant 80 intervals to the ring 10 are three (more or less) rising arms 11 in turn supporting and as well secured to the upper reflector 4. With such an assembly it will be noted that the frame 5 possesses rigidity and strength and 85 that the frame and upper reflector are in a sense unitary. A convenient construction of the reflector 4, as shown in the drawing, comprises its integral formation with an upper ledge 12 constituting a seat to receive 90 the contracted neck 13 of the shade 6.

The shade also, for certain preferred purposes of the invention, requires special construction and material. That is to say, it is an object to attain complete diffusion of the 95 light which emerges below the lamp in the reading area, while at the same time securing a decorative appearance of the fixture and a soft blending or diffusion of the rays in all directions. To accomplish this end, 100 it is found desirable to employ a silken shade made in two thicknesses; that is, with an outer layer of silk fabric 14, which may be shirred or otherwise ornamented, and an inner fabric or lining 15, which is stretched 105 tight on its frame to lie smoothly. The lining is also preferably of silk and white in color, so that a major portion of the light rays impinging thereon are reflected downwardly and only a minor portion of the 110 rays transmitted therethrough and through the outer fabric 14. For special purposes,

however, both the diffusing reflector 4 and the inner fabric 15 of the shade may be lightly tinted in color to thereby modify the quality of the light emerging from the 5 lamp.

It will be noted that the lamp described 10 yields no direct rays from the illuminant; that is to say, the major portion of the light after diffusion spreads about the base in the so-called reading area, and that portion which penetrates the shade has already 15 been diffused from the reflector 4 and filtered through the silk. It is further contemplated by the invention to select material for the shade of such quality in translucency 20 that the rays will merge in degree all about the fixture; in other words, so that no sharp lines or shadows will separate the reading area from that above. It is also to be noted 25 that the upper reflector 4 and the diffusing inner surface of the shade disperse the light rays so that no shadows are cast by the bracket arms 11 or other opaque parts or objects which might be positioned within the shade.

While as above described the invention is particularly designed for embodiment in portable lamps, it is to be noted that certain 30 of the advantageous features thereof could as well be employed in other types of fixtures. For example, the cupped, polished reflector 3 inclosing the illuminant might be suspended from above with the upper reflector 4 and shade 6 (in such instance the 35 latter preferably extending farther toward the lower plane of the reflector 2) arranged substantially as shown to constitute a pendant fixture.

Having described my invention, what I 40 claim as new and desire to secure by Letters Patent is:

1. In a portable lamp, in combination, a 45 standard, an illuminant supported thereby, an opaque cupped reflector about said illuminant arranged to intercept the direct rays below the upper horizontal plane of said illuminant and to direct such rays up-

wardly, an opaque diffusing reflector above and in alinement with said illuminant to direct laterally the rays impinging thereon, 50 a translucent silk shade laterally concealing said diffusing reflector, said shade having a mat inner lining adapted to direct downwardly a major portion of the rays impinging thereon, and a bracket supported by said 55 standard and supporting said diffusing reflector and said shade.

2. In a portable lamp, in combination, a vase-like standard, an illuminant concealed therein below the upper horizontal plane 60 thereof, a cupped polished reflector about said illuminant to direct rays upwardly, a diffusing reflector arranged above said illuminant to direct rays outwardly, a translucent silk shade laterally concealing said 65 diffusing reflector and spreading downwardly to substantially the upper plane of said standard, said shade having a mat white lining to direct a major portion of the rays downwardly, and means concealed 70 by said shade to support the latter and said diffusing reflector.

3. In a portable lamp, in combination, a vase-like standard, an illuminant mounted therein below the upper horizontal plane 75 thereof, a cupped polished reflector about said illuminant to direct rays upwardly, a diffusing reflector above and in alinement with said illuminant and having a mat white 80 surface to direct rays outwardly, a translucent silk shade fitting about and laterally concealing said diffusing reflector, said shade having a mat white lining to direct a major portion of the rays downwardly, and a bracket detachably mounted on said standard 85 and concealed by said shade to support the latter and said diffusing reflector.

In testimony whereof I affix my signature in the presence of two witnesses.

LORIN W. YOUNG.
